(57) **CLAIM**

The ornamental design for a crematory urn, as shown and described.

DESCRIPTION

FIG. 1 is a top view of the crematory urn showing the new design;

FIG. 2 is a bottom view thereof;

FIG. 3 is a side perspective view thereof;

FIG. 4 is a rear view thereof;

FIG. 5 is a side view thereof;

FIG. 6 is a rear perspective view thereof; and,

FIG. 7 is a front view thereof.

The broken lines in the drawings are included for the purpose of illustrating subject matter that forms no part of the claimed design.

1 Claim, 7 Drawing Sheets
